UNITED STATES PATENT OFFICE.

MILES WILBERT WILLIAMS, OF SHARON, PENNSYLVANIA.

RAIL-JOINT-BASE BOND.

No. 823,198.

Specification of Letters Patent.

Patented June 12, 1906.

Application filed January 29, 1906. Serial No. 298,417.

To all whom it may concern:

Be it known that I, MILES WILBERT WILLIAMS, a citizen of the United States, residing at Sharon, in the county of Mercer and State 5 of Pennsylvania, have invented certain new and useful Improvements in Rail-Joint-Base Bonds; and I do hereby declare the following to be a full, clear, and exact description of the invention, such as will enable others 10 skilled in the art to which it appertains to make and use the same.

For rail-joints I have produced a novel bonding device whereby the meeting ends of the rails are firmly connected and secured 15 and a joining maintained by a wedge action of the bonding device drawing the rail ends together and bracing them against sidewise displacement. The bonding device crosses the rail-joint and is secured in grooves having 20 vertical inclined shoulders in the base of each rail, and its construction is such that it forms a duplex wedge, and for that purpose each end has a shouldered and a wedge form acting with a compound function on each 25 rail—that is to say, drawing the rail ends together and preventing their separation—the object being to dispense with the bolts employed to fasten the rail ends, the chairs, and fish-plates together. In combination with 30 the duplex-wedge bond a box-chair is employed to hold the rail ends down and laterally, while the wedge-bond holds them together, making a smooth-tread joint and preventing jar to the passing train, for it is a distinguishing feature of the duplex-wedge bond 35 that it causes the weight of the train on either end of the joint to act to draw and hold the rail ends together in crossing the joint.

40 The accompanying drawings illustrate my invention, and in which—

Figure 1 shows the rail ends inverted and a base-groove in each terminating in a vertical socket in the web. Fig. 2 is a vertical longitudinal section of the rail-joint, its bonding device, and joint-supporting chair. Fig. 3 is a horizontal section of the rail-joint, bonding device, and joint-supporting chair. Fig. 4 shows the bonding device in side and end 45 views. Fig. 5 is a vertical cross-section of the rail-joint, its bonding device, and joint-supporting chair.

The web of each rail end has a vertical base-groove 1, open at the end of the rail and 50 terminating in a vertical socket 2 within the web. This socket joins the groove on each

side by a vertical shoulder 3, Fig. 3, which stands inclining upward from the base of the rail and away from its end, and the socket preferably tapers from its base to its upper 55 end. Each groove, with its terminal socket, extends about three inches within the web and terminates in the web at the base of the rail-head. The bonding device consists of a web 4, adapted to fit the groove in each rail-web and therefore crosses the rail-joint and has an abutment 5 at each end, which partially fills the end sockets of the web-grooves, each abutment forming a shoulder 6, inclining upward from the base toward the end of the 60 web, so that it has a wedge action on the shoulders of the socket of each rail-web, the action of which in inserting the bonding device in the grooves is to draw and secure the railends together, the wedge action being such 65 as to draw the joint tighter under the weight of the moving train. The web-abutments and the groove-shoulders afford security against the endwise separation of the rails, while the bond-web and its end abutments 70 afford security against lateral separation of the rails. Moreover, the wedge form of the bond-abutments provides a firm connection for the rail ends, and as aiding in this function the web of the bond is made of wedge form 75 in cross-section, and it will be noted that the base of the bonding device is on a plane with the base of the rail-flanges.

The chair is of the box type, having its rail side braces or fish-plates 7 integral with 80 the base-plate 8, the ends of which project beyond the ends of the side braces and are formed with depending flanges 9, which fit against and are spiked to the opposite sides of the cross-tie, while each side edge of the 85 projecting ends of the base-plate has a notch or recess 10 to receive spikes 11, driven into the cross-tie, so that the chair is fastened to the rail-flanges and to the cross-tie both endwise and sidewise. Openings 12 may be 90 made in the side edges of the braces to receive spikes 13, driven into the cross-tie, and these several means of securing the chair to the rail may be used together, rendering the box-chair a firm and durable fixture to the cross-tie. Looking at Fig. 2 the lower edge of the bonding device is seen resting upon the base-plate of the box-chair, and as the web of the bonding device is wedge-shaped in cross-section and its end abutments form wedges the 95 weight of the rails will constantly tend to force the web and its abutments into the rail 100 105 110

grooves and sockets, while the weight upon the rails keeps them down on the bond. Obviously the rail-sockets and the bonding-abutments may be of any suitable form so long as they are adapted to coact in a wedge action for drawing the rail ends together.

I claim—

1. In a rail-joint, the meeting ends having each a vertical base-groove open at the end of the rail, and terminating in an enlarged vertical socket within the web, tapering upward from the base of the rail and forming a vertical shoulder on each side of the groove inclining upward from the base and from the end of the rail, and a bonding device formed of a web fitting the rail-grooves and having at each end a vertical abutment fitting the tapering sockets of the grooves, each abutment having a shoulder on each side of the web abutting the inclined shoulders of the rail-grooves, whereby the bonding device is caused to have a wedge action on each rail to draw and hold them together at the joint.

2. In a rail-joint the meeting ends having each a vertical base-groove open at the end of the rail, terminating in an enlarged vertical socket within the web and having a vertical shoulder on each side of the groove, and a bonding device formed of a web fitting the rail-grooves and having at each end an abutment fitting the vertical sockets of the grooves and having a shoulder on each side of the web adapted to coact with the shoulders of the rail-grooves to cause a wedge action to draw and hold the rail ends together at the joint.

3. In a rail-joint the meeting ends having each a vertical base-groove open at the end of the rail and terminating in an enlarged vertical socket within the web forming a vertical shoulder on each side of the groove, a bonding device formed of a web having at each end an abutment fitting the vertical sockets of the grooves and having a shoulder

on each side of the web, the said shoulders of the grooves and of the bonding-abutments adapted to have a wedge action to draw and hold the rails together and the grooves and the bonding-web having a wedge form in cross-section whereby the bonding device is caused to have a longitudinal and a transverse wedging action upon the rail ends.

4. In a rail-joint the meeting ends having each a vertical base-groove open at the end of the rail, and terminating in an enlarged vertical socket within the web and having a vertical wedge-formed shoulder on each side of the groove, a bonding device formed of a vertical web fitting the rail-grooves and having at each end a wedge-formed abutment fitting the vertical wedge-formed sockets of the grooves, and a base box-chair having its ends turned down and spiked to the opposite sides of the cross-tie and otherwise spiked thereto and to the rail-flanges.

5. In a rail-joint, the meeting ends having each a vertical base-groove open at the end of the rail, terminating in an enlarged vertical socket within the web and forming a vertical shoulder on each side of the groove, and a bonding-web fitting the rail-grooves and having at each end a vertical abutment fitting the sockets of the grooves, each abutment having a shoulder on each side of the web abutting the shoulders of the rail-grooves and adapted to coact with them in causing a wedge action drawing and holding the rails at the joint, in combination with a box-chair supporting the rails laterally, and means for fastening the chair endwise, side- wise and vertically.

In testimony whereof I have signed my name to this specification in the presence of two subscribing witnesses.

MILES WILBERT WILLIAMS.
